UNITED STATES PATENT OFFICE.

ANDREW W. MILLER AND JOHN C. MILLER, OF MORRISONVILLE, ILLINOIS.

IMPROVEMENT IN WAGON-SEATS.

Specification forming part of Letters Patent No **148,128**, dated March 3, 1874; application filed January 19, 1874.

To all whom it may concern:

Be it known that we, ANDREW W. MILLER and JOHN C. MILLER, both of Morrisonville, in the county of Christian and State of Illinois, have invented certain new and useful Improvements in Wagon-Seats; and we do hereby declare the following to be a full, clear, and exact description of the invention, such as will enable others skilled in the art to which it pertains to make and use it, reference being had to the accompanying drawings, which form part of this specification.

Our invention relates to improvements on an invention for which Letters Patent were granted to John G. Armstrong and Jacob S. Armstrong, bearing date February 25, 1873, No. 136,123; and it consists in so arranging and constructing the hook-plate I that the said plate shall bear the upward and downward pressure of the compensating-rods, while it also forms the locking means, thereby dispensing with a separate locking-piece; but that our invention may be fully understood we will describe the same in detail.

Figure 1 represents a plan view of a block, D, with our improvements applied thereto. Fig. 2 represents a side view, and Fig. 3 a section through the lines *xx*, Fig. 1, in all of which the block is inverted.

D represents a block, such as described in the specification before referred to, to which the plates I, for receiving and holding the ends of the compensating-rods E are secured by screws or other suitable retaining means. The two ends of the compensating-rods E are turned up, as shown at E', and the projections thus formed are, by preference, filed square on their front and rear faces. They may, however, be otherwise formed, if desired. I represent our improved plates, which, in place of being formed flat over their whole surface, as described in the patent before referred to, are stamped, cast, or otherwise formed with chan-

nels or grooves *i*¹ *i*² and bearings *i*³, so constructed that when the parts are in position, as shown by the drawing, the channels or grooves *i*¹ of the extended portion I¹ shall rest upon the upper side of the compensating-rods E, while the channel or groove *i*² of the portion I² and the bearing *i*³ serve to retain the rods in position, and also to bear the downward pressure of the same. *i*⁴ are enlarged extensions of the grooves or channels *i*², adapted to receive and allow of the free movement of the projections E' of the rods E, the extent of such movement of the rods E in each direction being limited by the extensions *i*⁴.

By reason of the construction of the plate I, as described, the channels or recesses in the block D for the reception of the rods E are required to be cut only of a depth equal to half the thickness of said rods, thereby securing greater strength to said block. The weight or strain exerted on the rods E is wholly supported by the plate I. The block D is entirely relieved, and the enlargement of the grooves therein, in which the rods E move, and the cutting away and consequent weakening of the block, are effectually prevented.

Having thus described our invention, what we claim, and desire to secure by Letters Patent, is—

The combination, with the compensating-rods E and block D, of plates I, having extended portions I¹, channels or grooves *i*¹ *i*², bearings *i*³, and enlarged extended grooves *i*⁴, substantially as and for the purposes described.

In testimony that we claim the foregoing we have hereunto set our hands this 16th day of January, 1874.

ANDREW W. MILLER.
JOHN C. MILLER.
